United States Patent Office.

JOHN H. ROWLEY, OF FABIUS, NEW YORK.

Letters Patent No. 63,100, dated March 19, 1867.

IMPROVEMENT IN FENCE.

The Schedule referred to in these Letters Patent and making part of the same.

TO ALL WHOM IT MAY CONCERN:

Be it known that I, JOHN H. ROWLEY, of Fabius, in the county of Onondaga, and in the State of New York, have invented certain new and useful improvements in "Fences;" and do hereby declare that the following is a full, clear, and exact description thereof, reference being had to the accompanying drawings and to the letters of reference marked thereon.

In the annexed drawings, making part of this specification, A A represent the panels of the fence, which are constructed of the boards B B, which lie horizontally at a suitable distance apart, and which are firmly bound together by means of the slats or strips C' C'. The strips C C are secured in a vertical position on both sides of the ends of the boards, and the slats or strips C' C' are secured in a bracing manner on both sides of the boards, at suitable distances from the ends, say at about one-third of the length of the panel from each end. D represents a sliding-bar, which is placed between the top board and the one next to the top; and at one end of the panel, so that it can slide endwise, passing its outer end through and beyond the strips or slats which bind together that end of the panel at which the bar is located. This bar is provided on its outer end with a notch or shoulder, and it is also provided on its sides with two pins x x. The object of the pins is to prevent the bar from sliding too far either backwards or forwards. The notch or shoulder is to catch upon a plate or shoulder, or its equivalent, in an opening a in the side of one of the strips C, when it is desired to have two panels stand at right angles. When the panels are placed in a line the bar D slips out, and its end passes between the two strips C C, on the end of the panel to be joined on, and thus the two panels are kept together. F represents a staple, secured upon the upper edge of the top board. E represents a brace, which is provided with a loop at each end. The loop at the upper end embraces the staple F, while the loop at the lower end embraces a pin, G, which is driven into the ground in a slanting manner at the point where the end of the brace rests.

It will readily be seen that from the manner in which this brace is secured to the top board it may easily be changed from one side of the fence to the other simply by throwing its lower end over the panel and securing it upon a pin on that side. All of the braces may be left upon one side, or each alternate brace may be placed on the opposite side, to suit the nature of the case. This fence is simply placed upon the ground, as other portable fences are, without having its posts buried. The panels can be leaned at any angle desired by throwing and securing the lower ends of the braces further from the fence. It is often very desirable to lean the fence, as, for instance, when I wish to plough close to the fence, without having my whiffle or double-trees strike and drag against the fence. It is sometimes necessary to lean the fence to protect ditches or to prevent it (the fence) from being too much affected by strong winds. By drawing back the bar D from two adjoining panels the said panels may be swung around in any desired manner to allow of a vehicle passing through at any required point in the fence. I may use any kind of hinge to connect the upper end of the brace to the top board, but the hinge should admit of the brace being turned over the panel for bracing on either side.

What I claim is—

The arrangement of the panels A A with the braces E E, adjustably hinged to the said panels, and the sliding-bar D, the several parts being constructed and used substantially in the manner and for the purpose herein specified.

In testimony that I claim the foregoing I have hereunto set my hand this 16th day of January, 1867.

JOHN H. ROWLEY.
